UNITED STATES PATENT OFFICE.

GEORGE A. WADE, OF WINCHESTER, MASSACHUSETTS.

BUTTON.

SPECIFICATION forming part of Letters Patent No. 371,864, dated October 18, 1857.

Application filed August 11, 1856. Serial No. 210,619. (No model.)

To all whom it may concern:

Be it known that I, GEORGE A. WADE, a citizen of the United States, residing at Winchester, Middlesex county, State of Massachusetts, have invented certain new and useful Improvements in Buttons, of which the following is a specification.

My invention is a button having a perforated body and a detachable eye piece, and constructed, as fully set forth hereinafter, so as to permit the form and style of the button to be readily modified in certain respects, and facilitate the application and detachment of pieces of metal, fabric, or other material constituting the ornamental portion of the button.

In the drawings, Figure 1 is a transverse section showing my improved button secured to a piece of fabric. Fig. 2 is an edge view 20 of the button. Fig. 3 is a plan of the body portion. Fig. 4 is a section showing the body and eye-piece detached. Figs. 5, 6, and 7 are sections showing modifications. Fig. 8 is a plan of Fig. 7.

25 The body A of the button is of any suitable or desired form, size, and material, and is provided with a slot or opening, x, of circular or other shape, adapted to receive the stem a of an eye-piece, B. The eye-piece is provided at the outer end with a head or shoulder, b, of such size as to prevent the stem from passing completely through the opening, and at the lower end of the stem is a transverse eye, e, in such a position that 35 when the eye-piece is inserted in the opening in the body of the button the eye e will be in such a position that the thread securing the button to the fabric may be passed transversely through the eye, as shown in Fig. 1.

40 It will be seen that so long as the button is disconnected from the fabric the eye-piece can be detached, but that when the threads s are passed through the fabric and through the eye e, as shown in Fig. 1, the eye-piece is not only bound to the fabric, but the body of the button is also secured. By thus combining a perforated button-body and a perforated and headed eye-piece I am enabled to secure a number of advantages in the manufacture and use of buttons. For instance, the

head b of the eye-piece may be made of metal, pearl, or other material, or covered with any suitable fabric, so that by substituting different eye-pieces in connection with the same button-bodies a great variety of styles of buttons may be readily provided. Again, the eye-piece may be the means of clamping to the body of the button an ornamental disk or plate, d, perforated for the passage of the stem of the eye-piece and clamped to the face of 55 the button thereby, as shown in Fig. 5, or held in a recess in the body of the button, as shown in Fig. 6.

Instead of a plate the eye-piece may hold in position a disk of fabric, in which case it is desirable to secure the disk at the edges. One means of effecting this is by providing the button-body at the edge with a flange, f, having an inner annular recess, w, (see Fig. 4,) into which the edge of the flexible disk d 60 extends, as shown in Fig. 1, the stem a of the eye-piece passing through an opening in the center of the disk and the head b bearing upon and clasping the disk of fabric to the face of the button, so that the flexible disk is 65 held both at the center and at the edges.

The stem a of the eye-piece may be in one part with the head, and perforated, as shown in Figs. 1, 4, 5, and 6, or the stem may consist of metal in the form of an eye or loop, as 70 shown in Fig. 7, in which case the opening x in the body A of the button is a slot, as shown in Fig. 8. The stem and its eye may project below the lower face of the button, as shown in Fig. 6, or the button may have a transverse 75 or dished recess, u, at the under side, as shown in Figs. 1, 2, 3, 4, 5, and 7, so that the lower part of the button will rest against the fabric.

Without limiting myself to the precise construction and arrangement of parts shown, I 80 claim—

1. The combination, in a button, of a body having a depression, u, at the lower side and a central opening, x, and a detachable eye-piece consisting of a perforated stem provided 85 with a head, substantially as set forth.

2. The combination, in a two-part button, of a disk, the rigid perforated button-body A constituting the main part, and a rigid detachable eye-piece provided with a stem hav- 90

ing a slot at one end and a head at the other and adapted to secure the disk to the body of the button, substantially as set forth.

3. The combination of the body A, having 5 a central opening, a flange, and a recess, *w*, and a detachable eye-piece, B, with a stem adapted to pass freely in and out the central opening in the body, perforated at the lower end and having a head, *b*, at the upper end, 10 substantially as described.

In testimony whereof I have signed my name to this specification in the presence of two subscribing witnesses.

GEO. A. WADE.
